UNITED STATES PATENT OFFICE.

MALCOLM M. COPPUCK, OF PHILADELPHIA, PENNSYLVANIA, ASSIGNOR TO CYRUS S. DETRE AND CHARLES A. BLACKBURN, BOTH OF SAME PLACE.

FILE-BINDER.

SPECIFICATION forming part of Letters Patent No. 434,625, dated August 19, 1890.

Application filed May 1, 1890. Serial No. 350,228. (No model.)

To all whom it may concern:

Be it known that I, MALCOLM M. COPPUCK, a citizen of the United States, residing at Philadelphia, in the county of Philadelphia and State of Pennsylvania, have invented 5 certain new and useful Improvements in File-Binders; and I do hereby declare the following to be a sufficiently full, clear, and exact description thereof as to enable others skilled

10 in the art to make and use the said invention. This invention relates to temporary binders or clamps for holding documents and loose papers for convenient reference, and has for 15 its object the better facility of introducing and removing papers therefrom and the more secure holding thereof, the diminished liability to injure furniture by projections of fastening mechanisms, and also reduced cost in the production thereof.

20 To meet these requirements this invention consists in a pair of covers or front and back boards having at the back margin of one or both of each a thickened strip hinged thereto, and in such stiffened strip in one back or 25 cover staples inserted, to which cords are secured, and in the opposite one a clamping mechanism inserted in the recess or panel, so as to clamp the cord after passing through the documents and through the thickened 30 strip of the front cover.

The construction and operation of the invention is shown in the drawings annexed, and hereinafter fully described.

35 Referring to the drawings, Figure 1 shows a perspective view of a file-cover or temporary binder with papers secured therein; Fig. 2, a section in a vertical plane indicated by the dotted line $x-x$ in Fig. 1; Fig. 3, a transverse section in the vertical plane indicated 40 by the dotted line $y-y$ in Fig. 1. Fig. 4 shows the clamping device drawn on an enlarged scale.

A represents the front cover; B, the back cover; A', the hinge uniting the cover A and 45 the thickened strip A². A similar hinge B' and strip B² are attached to the back cover B.

The hinges A' and B' are made in any of the usual methods by gluing flexible cloth to pieces of pasteboard forming the cover and 50 back strip. The back strips A² and B² are made of two thicknesses of strong pasteboard.

Between the two thicknesses of the back strip B² are inserted, before cementing them or gluing them together, bent wires C C, forming staples C', which protrude inwardly and afford points of attachment for cords D. The cords D extend inwardly through holes formed in the strip A², passing through a small aperture E in the inner layer of pasteboard in said strip. In the outer layer of the 60 strip A², surrounding each of the apertures E, through which the cords D pass, is a rectangular sunken space or panel K, into which the leather covering of the back is molded, and in which is inserted a metallic plate G, 65 having guides or recurved edges G' upon its longer sides, in which a slide H is fitted to slide lengthwise.

A perforation G² in the plate G, coinciding in position with the hole E in the strip A², 70 serves to pass the cord through. The sliding plate A is made of elastic metal and slightly bowed in the center at one end and nearly flat, and made quite rigid at the other end by being curved over upon itself at H' to afford a hold for the finger-nail to slide the 75 plate by passing the cords through the papers J, placed in the file, and then through the apertures G², and, forcing the slide H over the cord, it is securely retained in position. It 80 may be further secured by passing it again through another aperture G³ inwardly to the inside of the binder. The plate G is secured in the recess or panel K by rivets K', the ridges G' and curved portion H' of the plate 85 H being sunk in the panel to avoid any protuberance beyond the surfaces of the strip A², and are thus protected from injury or from scratching and injuring furniture or other objects with which they may come in 90 contact. The ridges G' on the plate G serve to stiffen the same, and the plate G, by being a stronger and stiffer material than the strip A², more than compensates for the impaired stiffness thereof by reason of the portion cut 95 away in producing the panel K, and being secured by the rivets K' firmly to the strip A² contributes largely to strengthen this portion of the binder. The ridges G upon the edge of said plate perform the function of guides 100 for the plate H, and also constitute a very efficient bracing to the plate G.

Having described my invention, what I claim is—

1. In a file-binder, the combination of a perforated slide G, having parallel guides G' arranged to stiffen the same and guide the plate H, the whole constructed substantially as and for the purpose set forth.
2. In a file-binder for documents, the combination of the strip A², having sunken pan-

els therein with the stiffening-plates G², provided with ridges G', constructed and arranged to stiffen the same and to hold and guide the clamping-plate H, substantially as and for the purpose set forth.

MALCOLM M. COPPUCK.
